BURIAL CASKET

Anson C. Lamb, Cleveland, Ohio

Application September 11, 1946, Serial No. 696,094

4 Claims. (Cl. 27—14)

1

The invention relates to improvements in burial caskets.

As will be apparent from the objects hereinafter enumerated, the general purpose underlying my invention is to avoid, insofar as is reasonably possible, the usual background associated with the presence of death, and to retain, with appropriate dignity, the normal atmosphere of the household. With this general end in view the novel and improved casket now to be described, comprises an assembly of co-operating parts such that it can be arranged to resemble a common article of household furniture.

A further object of the invention is to provide a novel and improved burial casket which, when opened and suitably arranged, closely simulates the appearance of a conventional davenport or couch.

A further object of the invention is to provide a casket of the nature indicated in which the cover, the arms, and the bed construction are so disposable, individually and with relation to each other, that they cooperate to produce the appearance of a davenport, as above mentioned.

A further object of the invention is to provide a cover construction rearwardly slidable and tiltable to simulate the appearance of a davenport back, the cover being readily completely removable, if desired, by reason of the novel and improved separable complementary parts of the hinge means.

A further object of the invention is to provide at the opposed ends of the casket, a pair of respectively opposed hinged arms, normally housed and concealed in a compartment in the cover, but manually swingable outwardly to a position of rest on top of the casket end walls, when the cover is in open position, to further increase the general resemblance to a couch or davenport.

A further object of the invention is to provide improved bed means for supporting a body, such means being normally collapsed on the casket bottom, when the casket is shut, but being easily and rapidly erectable to the plane of the top edges of the casket walls, when the casket is open, by reason of the novel supporting structure and lifting leverage therefor. In the erected position the bed simulates the seat portion of a conventional davenport.

A further object of the invention is to provide novel and improved means whereby the casket handles are withdrawn into wall recesses

2

when not in use, leaving a substantially flat and uninterrupted wall surface as noted by ordinary superficial examination.

Other objects and advantages will be apparent from a study of the following specification in conjunction with the accompanying drawings, in which:

Fig. 1 is a perspective view of a closed casket construction in accordance with the teachings of the present invention;

Fig. 2 is an end elevational view showing the cover moved rearwardly to an intermediate position;

Fig. 3 is a view similar to Fig. 2 but showing the cover tilted vertically so as to constitute a rear wall, parts being broken away to reveal internal structure;

Fig. 4 is a fragmentary perspective view, somewhat enlarged, showing the detachable cover attaching means, the cover being separated from the body portion;

Fig. 5 is a sectional view, still further enlarged, taken on the line 5—5 of Fig. 4;

Fig. 6 is a front elevational view as seen from the right of Fig. 3, but with the inner lid in the cover raised to reveal the cover compartment and the end arms contained therein;

Fig. 7 is a perspective view with the cover in the position of Figs. 3 and 6, but with the arms swung outwardly, the inner lid closed, and the bed raised;

Fig. 8 is a front elevational view taken from the same position as Fig. 6, but with the front wall removed to reveal the bed in lowered position;

Fig. 9 is a view similar to Fig. 8 but showing the bed in erected position;

Fig. 10 is a perspective view of the bed and supporting mechanism removed from the casket to more clearly show the construction of the various movable elements;

Fig. 11 is a fragmentary front elevational view, showing the casket handle in inactive position;

Fig. 12 is a sectional view taken on the line 12—12 of Fig. 11.

Before the present invention here illustrated is described in detail, it is to be understood that the invention here involved is not limited to the details of construction or the specific arrangement of parts herein illustrated or described, as the invention obviously may take various forms. It also is to be understood that the phraseology or terminology herein employed is for the purpose of description and not of limita-

tion, the scope of the present invention being defined in the appended claims.

The improved casket to be herein described comprises a combination of cooperating structural features, each of which is in itself novel, as far as is known to me. The casket will now be described in detail, special attention being directed to the several novel features in turn.

The sliding and tilting cover is best shown in Figs. 1, to 5, inclusive. The appearance of the closed casket is fairly conventional, there being a body 20 and a cover 21. As will appear, however, the handles, when not in use, are withdrawable into recesses in the casket walls since one of the characteristics of preexisting caskets has been the prominent appearance of the handles. The cover 20 is slideable rearwardly on the casket body to the intermediate position shown in Fig. 2. At such point it is swingable to the vertical position shown in Fig. 3. It may at times be desirable to remove the lid, as indicated in Fig. 4.

Rearward sliding movement of the cover from the position of Fig. 1 to that of Fig. 2 is guided as follows, it being understood that the structure now to be described with respect to one end of the casket is duplicated at the other end, so that description of one end only is necessary. Depending from the end wall 22 of the cover is a right angled bracket 23 having an outturned flange 24. The end wall 25 of the casket body is grooved out to provide a guiding slot 26 within which flange 24 is adapted to travel when the casket cover slides on the body as above noted. A retaining member cooperating with flange 24 is provided by a bracket 27 which is fixed to the end wall 25 at its top, and which has an outturned flange 28 overlying but stopping short of the rearward end of slot 26. Such stoppage affords a sufficient clearance space 29 so that flange 24 may be inserted in or removed from slot 26 by swinging movement of the cover. It will be apparent that while flange 24 lies in slot 26 underlying flange 28, the cover 22 may be moved forwardly or rearwardly in sliding fashion, but cannot be tilted angularly or lifted vertically.

From the position of Fig. 2 the casket lid may be tilted to the position of Fig. 3, since as above indicated, the bracket 24 in such position can swing upwardly out of clearance space 29. Tilting movement is guided and effected by cooperation of the following elements. At the rearward end of the slot is a transversely extending pivot pin 32 fixed in the opposed slot walls. Fixed to the end wall 22 of the cover, and depending therefrom, is a downwardly and rearwardly inclined finger 33 which is adapted to move within slot 26 and rearwardly to a position beneath pin 32 when the cover is moved to the position of Fig. 2. Simultaneously the flange 24 has moved beneath the clearance space 29 at the top of slot 26. In this position, therefore, the cover may be tilted on the pivot 32 until it assumes a vertical position, a substantial portion of the cover extending above the level of the rear wall 35 of the casket body. In such vertical position a prong 36 carried by the cover, enters a recess 37 in the rear edge of end wall 25, thereby preventing accidental vertical displacement of the cover which might result in the cover falling behind the casket. If it is desired to completely remove the cover it may be tilted forward at the top, from the position of Fig. 3 toward that of Fig. 4, until the prong 36 clears from the recess 37. The cover can then be lifted to remove it completely from the body. In replacing the cover, the operations

described above may be performed in reverse order.

One advantage of the combined sliding and tilting movement of the cover will now be apparent. In the transition from the position shown in Fig. 2 to that of Fig. 3 the rear overhang of the cover is brought to a lapped contact with the rear casket wall, and since the center of gravity is rearwardly of the pivot 32, the cover position is stable, unless manually moved again to the position of Fig. 2, preparatory to closing.

The casket is provided with a pair of arms 40 at opposed ends thereof, the said arms when not in use being disposed within the cover. Referring to Figs. 6 and 7, the portion of the cover which vertically extends above the casket is provided with a recess 41 closed by, and concealed beneath, a movable panel or lid 42 which is here hinged along its upper edge. The lid is maintained in the closed position of Fig. 7 by any suitable means, cooperating frictional detent members 43, 44 being here shown. Each arm is carried by and swingable on a respective strap 45 which is hinged at 46 on the respectively adjacent inner end wall of the recess 41. The length and position of the straps are so proportioned and arranged that when the lid is opened, and the arm is swung outwardly to arrive at the position shown in Fig. 7, the face of each strap comes to a stop against adjacent wall 47, and the arms at such time are in vertical planar registration with the respective end walls 25 of the casket. When so disposed the arms fully conceal certain elements heretofore described such as the cooperating bracket members, the pivot finger and pivot pin elements, and also the slotted recess. As shown in Fig. 7 when the lid is closed the back and arms readily simulate corresponding members on an article of furniture of settee, davenport or daybed type. The strap construction 45 permits closure of lid 42 even when the arms are in their outwardly extended position.

It is my intention that when the deceased person has been prepared by the undertaker for general view, the impression created should be similar to that produced by viewing someone asleep on a couch. To further this end the remains should lie on or near the plane of the top edges of the casket side walls. For this purpose I provide a bed panel preferably of some textile material supported on a frame, said bed panel being normally lowered to rest on the casket bottom when the casket is closed, but being provided with novel means for raising it to a display level whenever desired. The bed panel and supporting means will now be described.

Referring generally to Figs. 8, 9 and 10, there is shown a generally rectangular frame 50 of longitudinal and lateral extent sufficient to occupy substantially the complete length and width of the clearance space within the casket. A textile panel 51 of canvas or similar material is stretched across the frame, and preferably secured beneath it. Such panel could be of a color and texture adapted to match the appearance of the rear wall and arms of the casket, as viewed in Fig. 7, although a loose coverlet or other drape may be superimposed thereon if desired.

The opposed ends of the bed panel are supported by a collapsible leg construction which is identical at each end of the bed so that one end only need be described. At each front corner at the head and foot of the panel is a bell crank lever 53 comprising an operating arm 54 and a leg 55. The arm and leg are fixed in angular

relationship to each other, being either formed integrally, or from separate pieces welded or otherwise united as desired. The bell crank arrangement thus formed is pivoted to the frame 50 at 56, namely the point of angular divergence of the arm and leg. The arm 54 is provided with an inwardly directed tab 54a which limits downward arm swing at the position shown in Fig. 10. A rear leg 55a is pivoted at the head and foot ends of the rear panel edge. The pair of opposed legs 55 and 55a at each end of the bed panel are connected by a transverse foot or bar 57 so that they are movable as a unit. The bar 57 limits upward and inward swing of the legs by coming into contact with the lower face of the bed panel in the collapsed position shown in Fig. 8. A tie link 58 is pivoted to the casket rear wall, and to the adjacent side edge of the panel frame, and acts as a control and guide in the operation now to be described.

Assume now that the bed panel is in the position shown in Fig. 8, namely collapsed on the casket inner bottom wall. To raise the bed to the position shown in Fig. 9 manual pressure may be applied to the arm 54 at the point 59, the pressure being directed in the direction of arrow A. A moderate lifting effort may be simultaneously exerted by inserting the fingers of the other hand beneath the panel in the neighborhood of the recess 60 in the panel end. Arms 54 and legs 55 swing as a unit in a circle until the bed end assumes the position shown in Fig. 9 or 10, at which time the tab 57 rests on top of frame 50, and the bar 54a, in the embodiment shown, abuts the lower end of the casket end wall 25. In this position, the bed panel lies in or just below the plane of the upper edge of the casket side walls, and in such position it is perfectly stable. The bed can be again collapsed by first raising the bed end slightly, until the bell crank lever formed by the arm and leg can be easily swung from the position of Fig. 9 to the position of Fig. 8. The function of link 58 is to act as a radius vector around the fixed pivot 61, thereby exercising a guiding and restraining effect to prevent substantial misalignment of the various co-operating movable parts.

Figs. 11 and 12 illustrate the disappearing handle structure. At a suitable location for each handle the casket wall is provided with a U-shaped recess 64 opening outwardly, for the reception of a handle 65 carried by a pair of side straps 66. The straps are pivoted on pins 67 which bridge the respective legs 68 of the recess. As viewed from the exterior the recess is substantially completely closed when the handle is swung downwardly and inwardly to inactive position, since exposed outer surface portions of the handles and straps may be covered with the same material, or finished in the same manner as the balance of the outer casket walls. For convenient insertion of the pins 67 in their operating position, the inner casket wall may be provided with suitable recesses 70, opening inwardly, and the pins may then be inserted as shown in Fig. 11. For convenience in pulling the handles outwardly from the inactive position to the active position, the bottom edge of the U-shaped depression 64 may be cut away, at 71, for the insertion of a finger tip to initiate handle movement.

It is of course obvious that the casket will present the appearance shown in Fig. 7 only when on display in the home, the specific appearance of the bed panel being concealed by a

suitable drape over or under the body of the deceased. The bed panel is lowered and the arms are retracted into their housing recess in the cover when the casket is being closed for transportation or interment.

5 What I claim is:

1. A burial casket comprising a casket body and a cover therefor, said body having a bottom wall, front and rear walls, and opposed end walls, each 10 said end wall being provided with an upwardly opening channel extending rearwardly along the top edge thereof, said cover being provided with a pair of fingers, one depending from each end thereof and alignable with, and insertable in, each 15 said channel, pivot means fixed in the rear end of each said channel, said cover being slidable rearwardly on said body until said fingers engage respective pivot means, said cover being thereupon pivotally tiltable to a vertical position partly above and partly below the plane of the top edge of said body walls, and a pair of arms 20 swingably attached to said cover and swingable to a position overlying respective end walls after the cover has been tilted as aforesaid.

25 2. A burial casket comprising a casket body and a cover therefor, said body having a bottom wall, front and rear walls, and opposed end walls, each said end wall being provided with an upwardly opening channel extending rearwardly 30 along the top edge thereof, said cover being provided with a pair of fingers, one depending from each end thereof and alignable with, and insertable in, each said channel, pivot means fixed in the rear end of each said channel, said cover being slidable rearwardly on said body until said fingers engage respective pivot means, said cover being thereupon pivotally tiltable to a vertical position partly above and partly below the plane 35 of the top edge of said body walls, said cover having an inwardly opening recess therein, a pair of end arms hingedly attached at respective ends of said recess, said arms being outwardly swingable to rest on adjacent end walls of the casket body when the cover has been tilted to the vertical position as aforesaid, and closure means for 40 closing said recess to conceal the same, said closure means being movable to permit movement of said arms into and out of said recess.

45 3. A burial casket comprising a casket body, 50 and a cover therefor, said body having a bottom wall, opposed front and rear walls, and opposed end walls, each said end wall being provided with an upwardly opening channel extending rearwardly along the top edge thereof, an elongated 55 member attached to each end wall adjacent its respective channel and having a flange horizontally overlying a front portion, but not all, of said channel, a bracket depending from each end of said cover and having a guide portion registrable with 60 and insertable in a respective channel, and slidable 65 therein from a position out of vertical alignment with said flange to a position in vertical alignment and sliding interlock with and beneath said flange, said interlock permitting only rearward and forward sliding motion of said cover until 70 said guide portion clears from beneath said flange, said cover and said body carrying mutually cooperating pivot elements engageable only when rearward sliding movement of said cover on said body causes clearance of said guide portion from beneath said flange, thereby permitting tilting movement of said cover to a vertical position adjacent said rear wall of said body.

4. A burial casket comprising a casket body, 75 and a cover therefor, said body having a bottom

wall, opposed front and rear walls, and opposed end walls, each said end wall being provided with an upwardly opening channel extending rearwardly along the top edge thereof, an elongated member attached to each end wall adjacent its respective channel and having a flange horizontally overlying a front portion, but not all, of said channel, a bracket depending from each end of said cover and having a guide portion registrable with and insertable in a respective channel, and slidable therein from a position out of vertical alignment with said flange to a position in vertical alignment and sliding interlock with and beneath said flange, said interlock permitting only rearward and forward sliding motion of said cover until said guide portion clears from beneath said flange, said cover and said body carrying mutually-cooperating pivot elements engageable only when rearward sliding movement of said cover on said body causes clearance of said guide portion from beneath said flange, thereby permitting tilting movement of said cover to a vertical position adjacent said rear wall of said

body, said cover having an inwardly opening recess therein, a pair of end arms hingedly attached at respective ends of said recess, said arms being outwardly swingable to rest on adjacent end walls of the casket body when the cover has been tilted to a vertical position as aforesaid, and closure means for closing said recess to conceal the same, said closure means being movable to permit movement of said arms into and out of said recess.
